UNITED STATES PATENT OFFICE.

FREDERICK W. BRITTIN, OF BIRMINGHAM, CONNECTICUT, ASSIGNOR TO
THE SILVER PLATE CUTLERY COMPANY, OF SAME PLACE.

DESIGN FOR A BUTTON-HOOK.

SPECIFICATION forming part of Design No. 16,766, dated July 6, 1886.

Application filed March 29, 1886. Serial No. 196,874. Term of patent 3½ years.

To all whom it may concern:

Be it known that I, FREDERICK W. BRITTIN, a citizen of the United States, residing at Birmingham, in the county of New Haven and State of Connecticut, have invented and produced a new and original Design for Solid Metal Button-Hooks; and I do declare the following to be a full, clear, and exact description of the same, reference being had to the accompanying drawings, forming a part thereof.

Figure 1 is a side elevation, and Fig. 2 is a plan view, of my newly-designed button-hook, the latter view showing an additional step between the handle and the button-hook.

The leading features of my design consist in a cylindrical handle having a bulb or ball at its outer end, and between the button-hook and the handle two or more shoulders and reduced portions.

A is the handle; B, the bulb or ball at its

outer end, which is joined to the handle by a neck, F; C, the button-hook; D, the reduced portions, and E, the shoulders.

The reduced portions and the handle are all made cylindrical.

I claim—

The design for button-hooks herein shown and described, the same consisting of a cylindrical handle, A, having a bulb or ball, B, at its outer end joined to the handle by a neck, F, a hook, C, and two or more reduced cylindrical portions, D, and concave shoulders E between said hook and the handle.

In testimony whereof I affix my signature in presence of two witnesses.

FREDERICK W. BRITTIN.
